WORK HOLDER

Frank S. Grylewicz, Cicero, and James C. Hannon
and Delbert V. Witsaman, Chicago, Ill.

Application May 31, 1945, Serial No. 596,960

4 Claims.

(Cl. 51—217)

The current invention pertains to certain valuable and innovative features of betterment and advantage in the structural characteristics and functional capacities of work-holders or jigs for efficiently and properly supporting and mounting work-pieces or bodies while they are operated upon and the invention deals more particularly, but not exclusively, with appliances of this type for holding the clutch-plates of automobiles and the like while their injured or roughened surfaces are reconditioned as by turning them smooth and/or grinding or polishing them.

Whereas a present preferred embodiment of the invention has been fully illustrated in the accompanying drawing, forming a part of this specification, and such apparatus has been fully described hereinafter, it is to be borne in mind that the invention is not necessarily limited and restricted to the precise and exact details thereof and that reasonable modifications therein may be availed of without departure from the substance and essence of the invention, as set forth in the appended claims, and without the loss or sacrifice of any of its material benefits and advantages.

For simplicity, in this drawing like reference numerals have been employed to designate the same structural parts throughout the several views thereof.

In this drawing—

Figure 1 is a plan view of a clutch pressure-plate mounted on the new work-holder, a portion of the plate being omitted for greater clarity of illustration;

Figure 2 is a fragmentary perspective view of the same elements;

Figure 3 is a perspective view of a portion only of one of the three clamps of the work-holder;

Figure 4 is an enlarged section on line 4—4 of Figure 1; and

Figure 5 is a cross-section on line 5—5 of Figure 4.

The round work-piece or clutch-plate 11, whose plane, top surface is to be smoothed or reconditioned by mechanism not shown, has three, equally-spaced, radially-disposed pairs of downwardly or rearwardly projecting adjacent lugs or ears 12, 12 with registered, round apertures 13, 13 therethrough by means of which with connecting instrumentalities, not shown, the pressure-plate, when forming part of the complete clutch-appliance in the automobile, is moved forwardly and rearwardly into operative and inoperative positions.

The novel and improved holder or mounting-appliance for such clutch-plate includes, in the present instance, a round, flat ring or base 14 of somewhat greater diameter than the plate 11 and having a flat, smooth, top surface.

At each of three points 120 degrees apart, the upper surface of such base 14 has an upstanding,

longitudinally-slotted, radially-disposed plate or bar 15 fastened edgewise thereon by a pair of screws 16, 16 extending upwardly through countersunk holes through the base 14, such element 15 extending slightly outwardly beyond the cylindrical edge of the plate 14, as presented most clearly in Figure 4.

The horizontal rectangular slots 17 of all three members 15 are parallel to and at the same distance above the top flat face of base 14.

Each of the three radial clamps has an inclined abutment-plate 18 fastened fixedly to the edge of the part 14 by a pair of screws 19, 19, as shown in Figures 3 and 4, such inclination being occasioned by the fact that the plate 18 bears against the protruding end of the corresponding member 15, such inclination being outwardly upwards so that the exterior face of element 18 is not vertical but very slightly inclined outwardly from the vertical.

In addition, each of the clamps includes a U-shape yoke 21, the inner end portions of whose parallel side-arms have registered holes 22, 22 of substantially the same diameter as that of the apertures 13, 13, which is approximately the same as the width of slot 17.

The intermediate cross-member of each yoke 21 has a central, screw-threaded hole therethrough accommodating a screw 23 fitted at its outer end with a handle 24 by means of which it may be turned and adjusted to bear in slightly downwardly directed manner against, and as determined by the outer sloping face of, the abutment-member 18, the width of the latter approximately equalling the space between the pair of parallel arms of the yoke 21, element 18 therefore determining the lateral position of the yoke and approximately that of the clutch-plate, the distance between the opposite faces of the two lugs 12, 12 being about that of the width of the member 18.

The round clutch-plate to be repaired or rehabilitated is mounted on the three radial holding or retaining clamps by inserting a one-headed pin or rod 25 at each clamp through the five, aligned, more or less equal-size apertures or holes 22, 13, 17, 13, 22 whereby the clutch-plate is supported by the three pins 25 resting on the bottom, smooth surfaces of the three slots 17, each member 15 being straddled by the lugs 12, 12.

Then the three screws 23 are tightened sequentially against the abutment-plates 18 to draw the three pins or rods 25 outwardly and firmly downward slightly on their corresponding slot bottoms, until the clutch-plate is substantially or actually centered and held down rigidly and securely in position.

In some cases, a precise and exact centering of the plate is not required, but, in any instance, miscentering in substantial degree is not possible

by any one clamp because the other two clamps preclude such occurrence, when the third clamp is tightened, due to the angular relations of the clamps to one another and the lugs on the clutch-plate to one another.

A single work-holder of this type will function properly with a large number of different sizes of clutch-plates even though the lugs of the latter vary somewhat in sizes and spacings apart.

Not only is this unique and original appliance distinctly efficient in its holding and maintaining characteristics but, as indicated, it has the distinct advantage that it can accommodate a large range of sizes or pieces of work and that, regardless of their dimensions within the scope of operation of the work-holder, they can be mounted with ease and despatch, a matter of material importance in determining the cost of reconditioning such bodies as clutch pressure plates, especially as contrasted with the workability of other appliances for doing the same work at present in general use.

As will be readily understood, in order to accommodate work-pieces of different dimensions, the sizes of the parts of the work-holder and their openings and shapes may be modified as occasion dictates and still be within the principles of the invention as defined in the following claims.

We claim:

1. In a work-holder having a base and a plurality of work-piece clamping-means on said base, the novel improvement of said work-piece clamping-means including in combination a plurality of work-piece supporting-members rigid with said base and radially arranged about a common center, said members having supporting surfaces all in the same plane, a U-shape yoke for each said member, the intermediate section of the yoke having a screw-threaded hole therethrough and arms of the yoke having registered apertures therethrough, a pin for each said member adapted to removably occupy said registered apertures in spaced-apart lugs on the work-piece and to bear on said supporting surface of the corresponding member, an abutment-plate for each said yoke rigid with said base, and an adjustable screw extended through the screw-threaded hole of each said yoke and adapted to bear at its inner end against the corresponding abutment-plate, whereby adjustment of the several screws clamps the work-piece fixedly in place for reconditioning.

2. In a work-holder having a base and a plurality of work-piece clamping-means on said base, the novel improvement of said work-piece clamping-means including in combination a plurality of work-piece supporting-members rigid with said base and radially arranged about a common center, said members having supporting surfaces all in the same plane, a U-shape yoke for each said member, the intermediate section of the yoke having a screw-threaded hole therethrough and arms of the yoke having registered apertures therethrough, a pin for each said member adapted to removably occupy said registered apertures in spaced-apart lugs on the work-piece and to bear on said supporting surface of the corresponding member, an abutment-plate for each said yoke rigid with said base, and an

adjustable screw extended through the screw-threaded hole of each said yoke and adapted to bear at its inner end against the corresponding abutment-plate, whereby adjustment of the several screws clamps the work-piece fixedly in place for reconditioning, the surface of each abutment-plate against which its screw bears being inclined whereby the yoke, when adjusted by its screw, pulls the pin outwardly and downwardly on said supporting surface.

3. In a work-holder having a base and a plurality of work-piece clamping-means on said base, the novel improvement of said work-piece clamping-means including in combination a plurality of work-piece supporting-members rigid with said base and radially arranged about a common center, said members having supporting surfaces all in the same plane, a U-shape yoke for each said member, the intermediate section of the yoke having a screw-threaded hole therethrough and arms of the yoke having registered apertures therethrough, a pin for each said member adapted to removably occupy said registered apertures in the yoke-arms and registered apertures in spaced-apart lugs on the work-piece and to bear on said supporting surface of the corresponding member, an abutment-plate for each said yoke rigid with said base, and an adjustable screw extended through the screw-threaded hole of each said yoke and adapted to bear at its inner end against the corresponding abutment-plate, whereby adjustment of the several screws clamps the work-piece fixedly in place for reconditioning, the supporting surface of each of said members being the bottom surface of a slot through said member and through which said pin is adapted to extend.

4. In a work-holder having a base and a plurality of work-piece clamping-means on said base, the novel improvement of said work-piece clamping-means including in combination a plurality of work-piece supporting-members rigid with said base and radially arranged about a common center, said members having supporting surfaces all in the same plane, a U-shape yoke for each said member, the intermediate section of the yoke having a screw-threaded hole therethrough and arms of the yoke having registered apertures therethrough, a pin for each said member adapted to removably occupy said registered apertures in the yoke-arms and registered apertures in spaced-apart lugs on the work-piece and to bear on said supporting surface of the corresponding member, an abutment-plate for each said yoke rigid with said base, and an adjustable screw extended through the screw-threaded hole of each said yoke and adapted to bear at its inner end against the corresponding abutment-plate, whereby adjustment of the several screws clamps the work-piece fixedly in place for reconditioning, the surface of each abutment-plate against which its screw bears being inclined whereby the yoke, when adjusted by its screw, pulls the pin outwardly and downwardly on said supporting surface, the supporting surface of each of said members being the bottom surface of a slot through said member through which the corresponding pin is adapted to extend.
